DESIGN FOR A GLOVE

Lucie J. Maclear, New York, N. Y., assignor to Van Raalte Company, New York, N. Y., a corporation of New York

Application December 2, 1936, Serial No. 66,254

Term of patent 3½ years

To all whom it may concern:

Be it known that I, Lucie J. Maclear, a citizen of the United States, residing in New York, county and State of New York, have invented a new, original, and ornamental Design for a Glove, of which the following is a specification, reference being had to the accompanying drawing, forming a part thereof.

In the drawing:

Fig. 1 is a plan view of the back of a glove showing my new design.

Fig. 2 is a plan view of the front thereof.

The design is characterized by a relatively heavy piping extending around the cuff edge, in combination with a double row of horizontal, spaced apart, grommeted eyelets on the back of the glove, through which is threaded a ball tipped lacing as shown.

I claim:

The ornamental design for a glove, as shown and described.

LUCIE J. MACLEAR.
